OTHER PUBLICATIONS

Design U.S. Appl. No. 29/824,123, filed Jan. 21, 2022 entitled
“Vehicle Wheel”.

(Continued)

Primary Examiner — Adam C Mager

(74) *Attorney, Agent, or Firm* — Dinsmore & Shohl LLP

(57) **CLAIM**

The ornamental design for a vehicle wheel as shown and described.

DESCRIPTION

FIG. 1 is a front perspective view of a vehicle wheel illustrating an embodiment of our new design;

FIG. 2 is a rear perspective view thereof;

FIG. 3 is a front view thereof;

FIG. 4 is a rear view thereof; and,

FIG. 5 is a side view thereof.

The broken lines in the drawings illustrate portions of the vehicle wheel that form no part of the claimed design. The dot-dashed lines are included for the purpose of illustrating boundary lines and form no part of the claimed design.

1 Claim, 5 Drawing Sheets
